UNITED STATES PATENT OFFICE.

JOHN M. SAILER, OF JANEVILLE, WISCONSIN, ASSIGNOR OF ONE-HALF TO WILLIAM MUSSER, OF IOWA CITY, IOWA.

TRACTION-ENGINE.

1,044,578.

Specification of Letters Patent.

Patented Nov. 19, 1912.

Application filed July 15, 1910. Serial No. 572,157.

To all whom it may concern:

Be it known that I, JOHN M. SAILER, a citizen of the United States, residing at Janesville, Wisconsin, have invented certain new and useful Improvements in Traction-Engines, of which the following is a specification.

This invention relates to improvements in traction engines.

10 The main objects of this invention are: First, to provide an improved traction engine which is very powerful in proportion to the power units of its driving motor. Second, to provide an improved traction engine which may be manipulated and turned in a small space. Third, to provide in a traction engine traction wheels which may be adjusted to meet varying conditions under which the engine may be operated.

15 20 Further objects, and objects relating to structural details, will definitely appear from the detailed description to follow.

I accomplish the objects of my invention by the devices and means described in 25 the following specification.

The structure described constitutes one effective embodiment of my invention.

Other embodiments would be readily devised by those skilled in the art.

30 The invention is clearly defined and pointed out in the claims.

A structure constituting an effective and preferred embodiment of the features of my invention is clearly illustrated in the accompanying drawing, forming a part of this 35 specification, in which:

Figure 1 is a side elevation of a structure embodying the features of my invention, the motor not being shown. Fig. 2 is a plan view of the structure shown in Fig. 1, portions being broken away to show structural details, and the adjustment of the caster-wheel being indicated by dotted lines. Fig. 3 is an enlarged detail vertical section taken 40 on a line corresponding to line 3-3 of Fig. 1. Fig. 4 is a detail vertical section taken on a line corresponding to line 4-4 of Fig. 3, showing details of the driving connections. Fig. 5 is a detail vertical section taken 45 on a line corresponding to line 5-5 of Fig. 2, showing the cranks and connections for adjusting the traction wheels. Fig. 6 is an enlarged detail vertical section taken 50 on a line corresponding to line 6-6 of Fig. 3, showing structural details of the traction

wheels. Fig. 7 is a detail section taken on a line corresponding to line 7-7 of Fig. 2, showing structural details of the hitch device. Fig. 8 is a detail perspective view of the hitch device removed from the frame. 60 Fig. 9 is a detail perspective view of the rim or tread of the traction wheels.

In the drawings, similar reference characters refer to similar parts throughout the several views, and the sectional views are 65 taken looking in the direction of the little arrows at the ends of the section lines.

Referring to the drawing, the frame 1 is shown in the drawing largely in conventional form, as its structural details form no 70 part of the present invention. It will be understood that in practice the frame will be made up of pieces, suitably connected, whereas in the drawing, the frame is shown as formed in one piece. 75

The engine proper, or motor, is not illustrated. I preferably use an explosion engine.

The axis of the traction wheels 2 is formed of sections, as 3 and 4, each section being 80 preferably provided with bearings 5 and 6. The traction wheels are connected to the axle sections by universal joint connections so that they may be adjusted thereon relative to the vertical and horizontal planes 85 of the axle for the purpose of steering, and also to tilt the wheels and secure the best traction under varying conditions in the operation of the engine. This universal joint connection consists of spherical hubs 90

7. On the axles are spherical bearing members 8 having horizontally-disposed journals 9 arranged transversely of the axle, (see Figs. 3 and 6). These journals are arranged through the axle, as illustrated, the axle, for convenience in assembling, being provided with a longitudinal slot 10 in which the journal is retained by the screw 11. The intermediate spherical bearing members 12 are arranged on the bearing members 8 and 95 journaled on the journals 9 thereon. These intermediate bearing members 12 are provided with vertically-disposed journals 13, the hub being provided with suitable bearings 14 therefor. The intermediate bearing member 12 coacts with the axle bearing member 8 and with the hub. By this arrangement, a universal joint connection is secured for the wheels to the axle, which permits the tilting of the wheels relative to 100 105 110

the vertical and horizontal planes of the axle.

For convenience in assembling, the wheels are provided with webs 15 to which the hubs 5 are secured. The hubs are, for convenience in assembling, formed of sections having flanges 16 and 17 therein, the flanges being secured together by rivets 18. The bearings 14 for the journals 13 are formed one half 10 in each hub flange. The flange 16 is offset or shouldered at 19 to receive the web 15. The hub flanges are provided with annular bearings 20 for the annular bearing members 21 to which the adjusting and supporting 15 means for the wheels are connected. Each adjusting means consists of a shaft 22, having threaded ends threaded into the coupling members 23, which are secured to the blocks 24 on the bearing members 21 by 20 means of the pivots 25, the ends of the coupling members being forked to embrace the blocks. (See Figs. 2 and 3.) The shafts 22 are supported in the elongated bearings 26, which permits a slight lateral movement 25 of the shafts, the shafts being held against longitudinal movement by the collars 27. These shafts 22 are arranged one in the vertical and the other in the horizontal plane of the axle. For convenience in assembling, they are formed of sections secured 30 together by clips 28. The shafts are adjusted, in the structure illustrated, from the cranks 29, which are mounted on the standards 30 in convenient relation to the operator, the operator's seat or platform not being 35 here illustrated as it would obscure certain of the operative parts. The cranks are provided with sprocket wheels 31, which are connected to the sprocket wheels 32 on the 40 shafts 22 by means of the sprocket chains 33. (See Figs. 2 and 5.) By this arrangement, the traction wheels can be adjusted or tilted relative to the horizontal as well as vertical planes of their axle so that the steering is effected 45 through the traction wheels, and also so that the greatest tractive power can be secured and the wheels adjusted to prevent slipping on side hills or the like.

My improved traction engine is especially 50 designed by me for use in hauling loads or for farm traction purposes, and it is desirable that the structure be as light and simple as possible, and, at the same time, be easily and conveniently operated.

I provide the traction wheels with improved rims 34, having alternately-disposed V-shaped tapered grooves 35 therein, forming V-shaped lugs extending substantially across the tread, the lugs merging into each other, 60 as clearly appears from the drawing. This form of rim or tread for the traction wheels is of especial advantage in connection with the tilting of the wheels.

The driving connections preferably 65 consist of the driving shaft 36, which in the

structure here illustrated, is the crank shaft of the motor. On this driving shaft is a pair of pinions 37 and 38, which are secured to the shaft by the clutch 39, the clutch preferably being the structure shown in my pending application filed May 10, 1910, Ser. No. 560,404. The levers for actuating the 70 clutches are not here illustrated.

On the axle section 3 are gears 40, 41, and 42, all of the same size. The gear 42 is 75 fixed to the axle to revolve therewith, while the gears 40 and 41 are revolvably mounted on the axle and arranged in mesh with the pinions 37 and 38, respectively, on the driving shaft. Pinions 43 and 44 are fixed to the gears 40 and 41, respectively. 80

Arranged parallel with the axle is a transmission shaft 45. Fixed to this shaft to revolve therewith is a gear 46 meshing with the pinion 43. Revolvably mounted on the transmission shaft 45 is a gear 47, meshing with the pinion 44. Fixed to this gear 47 to revolve therewith is a pinion 48 meshing with the gear 42 on the axle sections. A clutch 49 is provided for securing the gear 40 to the axle section 3. When this clutch 90 is in engagement, the axle section 3 is driven in a reverse direction. The shifting means for this clutch 49 are not illustrated. On the axle section 4 is a gear 50 arranged in mesh with the pinion 51 on the transmission shaft 45. The gears and pinions are of such dimensions that both axle sections are driven at the same speed, the section 3 being driven for one speed through the train of gears 38, 41, 44, 47, 48 and 42, while the other is 100 driven through the train of gears 37, 40, 43, 46, 51 and 50. It is obvious that the axle sections may be driven independently or simultaneously through the manipulation of the clutches 39. This is of advantage in 105 steering the engine. The section 3 can be driven in a reverse direction by means of the clutch 49, as described, while the section 4 is driven in the reverse direction through 110 the auxiliary transmission shaft 52, which is connected to the main transmission shaft through the pinions 53 and to the gear 50 through the pinion 54. (See Figs. 2, 3 and 4.) The pinions 51 and 53 are secured to 115 their respective shafts by clutches which are adapted to be manipulated to disconnect both or connect either of the pinions, a double yoke 55 being provided to engage the shifting members of the clutch, the yoke being operated through a post 56 which is extended into convenient reach of the operator. To provide another speed, I mount on the 120 transmission shaft a gear 57 having a clutch connection therewith. The means for engaging the clutch 59 with the gear 57 are not here illustrated. I preferably secure to this gear a drum or windlass 58.

Revolvably mounted on the axle section 4 is a gear 60, having a hub-like clutch mem- 130

ber 61 thereon and a clutch member 62 arranged within the member 61. (See Fig. 3.) The gear 60 is adapted to be shifted longitudinally to throw the clutches into engagement. Splined to the axle sections 3 and 4 are clutch members 63 and 64, adapted to coat with the clutch members 61 and 62, respectively on the gear 60. These clutch members are splined to the axle section and 10 are held yieldingly in position by the springs 65 carried by the collars 66 and 67, so that the clutches are permitted a ratchet action. The collar 66 is adapted to receive the inner ends of both axle sections, and also to serve 15 as a bearing support for the clutch member 61, the parts thus assisting in keeping the shaft sections in alinement. By this arrangement of parts, when the engine is driven through the gears 57 and 60, the axle 20 sections are driven as a continuous axle. At the same time, in turning, variable speed is permitted. The drum 58, through this connection, may be driven independently or simultaneously with the axle. The advantage 25 of this arrangement is that should the engine become stuck owing to the traction wheels striking soft or slippery ground, the rope 68 may be attached to some fixed object and the engine thus assisted; or, the 30 windlass can be used for various purposes when running free from the axle, as for instance, when the engine is used in hauling hay, the windlass can be used for hoisting it.

To assist in controlling the engine, I provide 35 the traction wheels with independent brakes. These consist of the brake wheels 69 on the axle sections, having brake bands 70 thereon. These bands are controlled by the levers 71 which are pivoted to the frame 40 at 72 and 73 and provided with laterally-projecting arms 74 having foot pieces 75 thereon. These foot pieces are disposed so that either may be engaged, or both at the same time.

The engine is provided with a third or 45 caster wheel 76. This wheel has a spindle 77 which is mounted in the bearing 78 provided with means for clamping the spindle, as the bolt 79, the bearing being split at 80. The bearing is supported on the arm 81, 50 which is secured to the frame by the vertical pivot 82, the pivot being preferably a bolt so that the supporting arm may be clamped in its adjusted positions, see dotted lines in Fig. 2. The bearing 78 is supported in this 55 arm by means of the horizontally-disposed pivot 83 arranged in a suitable bearing in the supporting arm, the supporting arm being provided with clamping bolts 84. By this arrangement of the third or auxiliary wheel, it can be swung to one side, as shown by dotted lines in Fig. 2, or swung up out of operative position, as there illustrated. When the engine is hitched to the tongue of 60 a wagon or a machine such as a harvester,

the third wheel may be shifted to its inoperative position, or swung out of alinement with the tongue. I preferably provide the auxiliary wheel with a lever 85.

My improved hitch device consists of a pole holder 86, which is pivoted at 87 to the bracket 88. This bracket is pivotally mounted on the frame, the frame being provided with a bearing 89 for the disk-like bearing member 90 on the bracket. The pivot 91 for the bracket is centrally arranged relative to the bearing 90. The pole holder 86 is provided with an eye 92 for the attachment of the draft chain. The pole holder is provided with means whereby free vertical movement is permitted, or it may be clamped in its adjusted position. This means consists of the rods 93, which are arranged through ears 94 on the pole holder, the rods being threaded and provided with 95 clamping nuts 95.

My improved traction engine is very easily handled or manipulated, and is very powerful in proportion to the power units of its driving motor, and is adapted for use 90 under a very great variety of conditions. I have especially designed the same for farm purpose, although it is equally advantageous for road work. I desire to remark in this connection, that I am aware that my 95 improved engine may be very greatly varied in structural details without departing from my invention, and I desire to be understood as claiming the same specifically in the form illustrated, as well as broadly within the 100 scope of the appended claims.

Having thus described my invention, what I claim as new and desire to secure by Letters Patent is:

1. In a structure of the class described, 105 the combination of the traction wheels; an axle; spherical hubs for said wheels; spherical bearing members secured to said axle and having journals arranged transversely of said axle; intermediate spherical bearing members arranged on said bearing members on said axle and journaled on the said journals thereof to coat with said hubs, said intermediate bearing members being provided with journals for said hubs disposed at right angles to the said journals of said bearing members on said axle; and means for adjusting said wheels on the said journals comprising bearings on said 110 wheels; annular bearing members arranged 115 thereon; shafts having threaded ends; coupling members into which said shafts are threaded pivotally connected to said annular bearing members; and bearings for said shafts.

2. In a structure of the class described, 120 the combination of the traction wheels; an axle; spherical hubs for said wheels; spherical bearing members secured to said axle and having journals arranged transversely 125 of said axle; intermediate spherical bearing members arranged on said bearing members on said axle and journaled on the said journals thereof to coat with said hubs, said intermediate bearing members being provided with journals for said hubs disposed at right angles to the said journals of said bearing members on said axle; and means for adjusting said wheels on the said journals comprising bearings on said 130 wheels; annular bearing members arranged thereon; shafts having threaded ends; coupling members into which said shafts are threaded pivotally connected to said annular bearing members; and bearings for said shafts.

- of said axle; intermediate spherical bearing members arranged on said bearing members on said axle and journaled on the said journals thereof to coact with said hubs, said 5 intermediate bearing members being provided with journals for said hubs disposed at right angles to the said journals of said bearing members on said axle; and means for adjusting said wheels on the said journals.
- 16 3. In a structure of the class described, the combination of the traction wheels; an axle having longitudinally slotted ends; bearing members secured to said axle and having journals arranged transversely of 15 said axle engaging the said slots therein, said bearing members being sleeved upon said axle; screws threaded longitudinally into said axles to secure said journals in said slots; and intermediate bearing members arranged on said bearing members on 20 said axle and journaled on the said journals thereof, said intermediate bearing members being provided with journals for said wheels disposed at right angles to the said journals of said bearing members on said axle.
4. In a structure of the class described, the combination of the traction wheels; an axle bearing member secured to said axle and having journals arranged transversely 30 of said axle; and intermediate bearing members arranged on said bearing members on said axle and journaled on the said journals thereof, said intermediate bearing members being provided with journals for said wheels disposed at right angles to the said journals of said bearing members on 35 said axle.
5. In a structure of the class described, the combination of the wheels; an axle; bearings for said wheels comprising journals arranged transversely of the axle and secured thereto; bearing members journaled 40

on said journals on said axle and provided with journals for the wheels arranged at right angles to said journals on said axle; and independently operatable means for adjusting said wheels on both of their said journals, for the purpose specified. 45

6. In a structure of the class described, the combination of the wheels; an axle; bearings for said wheels comprising journals arranged transversely of the axle and secured thereto; bearing members journaled on said journals on said axle and provided with journals for said wheels arranged at 50 right angles to said journals on said axle; and means for adjusting said wheels on their said journals comprising bearings on said wheels, annular bearing members arranged thereon, shafts having threaded ends, and coupling members into which said shafts are threaded pivotally connected to said annular bearing members, one of said shafts being disposed in a plane at right angles to the axes of each of said journals. 55

7. In a structure of the class described, the combination of the wheels; an axle on which said wheels are mounted to be adjusted on axes disposed transversely to said axle; and means for adjusting said wheels on their 60 said axes, comprising bearings on said wheels, annular bearing members arranged thereon, a shaft having threaded ends, coupling members into which said shaft is threaded pivotally connected to said annular bearing members, and bearings for 65 said shaft.

In witness whereof, I have hereunto set my hand and seal in the presence of two witnesses.

JOHN M. SAILER. [L. s.]
